ALEXANDER CLARKE, OF EASTLAND, TEXAS, AND HORACE BUTLER, OF WEST CHESTER, PENNSYLVANIA, ASSIGNORS TO UNITED HYDRO CARBONS COMPANY, OF WEST CHESTER, PENNSYLVANIA, A CORPORATION OF WEST VIRGINIA

PRODUCTION OR RECOVERY OF LIGHTER HYDROCARBONS

Application filed August 7, 1926. Serial No. 127,718.

This invention relates to the production or recovery of lighter hydrocarbons. It is directed to the production or recovery of lighter hydrocarbons in liquid form from vapors or gases containing the desired hydrocarbons and perhaps other hydrocarbons regardless of whether such vapors or gases occur naturally, or are produced by distillation of mineral oils or bituminous coal or similar substances rich in hydrocarbons, or are produced by distilling a mixture produced by absorbing liquefiable or other hydrocarbons in a heavier liquid hydrocarbon or even a solid substance, or are produced as a by-product or intermediate product in refineries. This invention is also directed to the distillation of such lighter hydrocarbons from mixtures containing heavier hydrocarbons regardless of whether such mixtures occur naturally, as in petroleum, or are a product of distillation, mixture or absorption, or an intermediate or by-product of oil refining. This invention is also directed to the production of mixtures that are to be distilled as by the absorption of desired lighter hydrocarbons in an absorption medium. It is also directed to the achievement of any two or more of such objects or results by conjoint use of several features of our invention. Thus our invention comprises the liquefaction by novel methods of lighter hydrocarbon vapors, and comprises the separation of lighter hydrocarbons from heavier hydrocarbons by distillation that involves novel features and also comprises the production by novel methods, preliminary to distillation, of mixtures of lighter hydrocarbons with heavier hydrocarbons by the absorption of the desired lighter hydrocarbons in heavier hydrocarbons. An object of our invention is to provide a process and apparatus for the practice thereof which comprises features whereby lighter hydrocarbons are absorbed by an absorption medium or menstruum and whereby lighter hydrocarbons are separated to a high degree by distillation from mixtures containing heavier hydrocarbons regardless of whether such mixtures occur naturally or are artificially produced or constitute an intermediate or by-product, and whereby the

desired hydrocarbons are liquefied from vapors or gases containing the same as by compression and cooling, and whereby such a resulting liquid product may be brought to a condition wherein it meets commercial requirements as to stability under specified temperatures and pressures. It is a further object of our invention to provide a process and apparatus wherein the foregoing features contribute individually, but to a greater degree through cooperation and conjoint use, to the attainment of the desired ends. 55

Our invention is particularly well adapted to the production or recovery from natural gas of gasoline that meets commercial requirements as to stability under specified temperatures and pressures. Our invention will be described in connection with the production of such gasoline as that operation well illustrates the features of our invention, 65 but the applicability of the features of our invention and of the whole or various parts thereof in the recovery of other hydrocarbons in liquid form, and to the distillation of other hydrocarbons from mixtures of hydrocarbons, and to the absorption of other hydrocarbons will be apparent to those skilled in the art. 75

Accordingly it is a specific object of this invention to obtain or recover from natural gas a suitably stable gasoline comprising a high proportion of those hydrocarbons of the natural gas which are desirable constituents of such gasoline. To this end, it is a further object of this invention to recover or produce from natural gas, in the form of a gross product comprising "wild" gasoline containing low-boiling hydrocarbons that are maintained in liquid form at atmospheric temperature only under pressure above atmospheric pressure, as high a proportion as possible of the total hydrocarbons present in the natural gas. Careless reduction of the pressure under which such wild gasoline is maintained results in the volatilization and escape of low-boiling hydrocarbons and in the loss of desirable and higher-boiling hydrocarbons that are carried away in vapor form with the volatilized low-boiling hydrocarbons. The vaporization of low-boiling hydrocarbons 80 85 90 95 100

produces refrigeration that is useful when carefully employed in preventing such loss of desirable hydrocarbons; and it is an object of this invention to produce a gross product that contains a high proportion of low-boiling hydrocarbons and is thereby well suited to stabilization or weathering steps in which loss of desirable hydrocarbons is so prevented. The increase of gross product obtained 10 by our process over that of prior processes contains all constituents of such product but contains the lower-boiling constituents in greater proportion.

We have found that in the production of 15 gasoline from natural gas in the practice and use of our invention various features thereof contribute individually, but to a greater degree through cooperation and conjoint use, to the production of a gross product containing 20 as high a proportion as possible of the hydrocarbons of the natural gas, which proportion includes a high percentage of low-boiling hydrocarbons, and to the production of a final product containing a high proportion 25 of the hydrocarbons of natural gas that are suitable constituents of stable gasoline. We have found, in the practice of our invention, that the proportion of hydrocarbons recovered from natural gas, both in the gross 30 product and in the final or stable, product, is greatly increased if the vapors distilled from the absorption medium are subjected to compression and condensation without previous removal therefrom of any part of such vapors 35 and particularly without previous removal therefrom of the higher-boiling constituents or so called "heavy ends" of such vapors. In this connection we have found that a higher proportion of the hydrocarbons of the gas, 40 including low-boiling hydrocarbons, is not only carried into the gross product but is retained in the final or stable product when the condensation of the lower-boiling substances occurs simultaneously with the condensation 45 of the higher-boiling substances. In other words, we have found that a higher proportion of the hydrocarbons of the gas is condensed and brought into the gross product and retained in the final product if a high 50 proportion, or the maximum, of higher-boiling substances is carried through or treated in the compressing and condensing operations together with the lower-boiling substances. To this end still vapors that include 55 as large a proportion as possible of the absorbed hydrocarbons are subjected simultaneously or in one operation to compression and subsequent condensation. Thus, if any hydrocarbons, particularly heavy hydrocarbons, 60 have been condensed from the still vapors prior to compression and condensation, it is within the spirit of our invention to return such condensed hydrocarbons, preferably in vapor form, to the vapors passing to 65 the compression and condensation operations.

Such previously condensed hydrocarbons may be introduced into the compressed vapors passing to the cooling operation in which case they will cool the compressed vapors, particularly if expanded into the compressed 70 product.

The more thoroughly the absorption medium is stripped of previously absorbed hydrocarbons of the natural gas prior to reuse in the absorption operation the greater will be the proportion of hydrocarbons absorbed by it from the gas and the greater will be the percentage of low-boiling hydrocarbons included in such absorbed hydrocarbons; and such thorough stripping brings into the distilling and condensing and stabilizing operations that greater proportion of absorbed hydrocarbons. We have found that in the practice of our invention such thorough stripping can be attained and that the advantages due thereto may be realized to a high degree in our process; and we have found that such thorough stripping may be economically practiced in our process and will augment the effectiveness of other parts thereof. Steam distillation of a liquid absorption medium is effective to strip the absorption medium to a high degree but in separating the condensed steam some of the heavy hydrocarbons are condensed and difficulties are imposed upon that step of our invention wherein the lighter or lower-boiling hydrocarbons are condensed in the presence of, or in contact with, condensing heavier hydrocarbons, and the removal of heavier hydrocarbons increases the partial 95 pressure of the remaining vapors, and losses occur in separating the water from the condensed hydrocarbons. If the distillation is carried out without the use of steam as in a fire still, the vapors may all be passed together to the compressing and condensing operation. If complete stripping without steam cannot be accomplished or presents difficulties such as injury to the absorption medium, then distillation without steam may be carried as far as practicable and may then be followed by steam distillation. In such case the fire distillation sends as much as possible of the absorbed hydrocarbons directly to the compressing and condensing operations and the subsequent steam distillation will thoroughly strip the absorption medium. Furthermore, particularly in the absorption of gasoline hydrocarbons from natural gas from certain sources, additional beneficial effects of steam distillation are that the vapor tension of the absorption oil is greatly lowered and unsaturated hydrocarbons are distilled off so that they may be brought into the final product by other features of our invention, whereas they might otherwise produce undesirable sludge in the absorption oil as by polymerization there. In such double distillation the hydrocarbons distilled off by the steam will constitute but a small quan- 100 105 110 115 120 125 130

tity of the total hydrocarbons distilled off from the absorption medium and will include but a small quantity of hydrocarbons that will condense with the steam. Such hydrocarbons as condense with the steam may even be discarded without fatal impairment of the efficiency of our process or they may be returned in vapor form to the vapors passing from the fire still to the compressor or in liquid form or vapor form to the product of the fire still that is passing from the compressor to the condenser. Vapors evolved by the steam distillation that do not condense when the steam is condensed will be returned to the vapors that are passing from the fire still to the compressor.

We have also found that while the vapors passing to the compressing and condensing steps in the practice of our invention contain a large proportion of low-boiling hydrocarbons as well as higher-boiling hydrocarbons, such vapors including both low-boiling and high-boiling hydrocarbons with perhaps a predominance of the former as are not condensed when first passed through the condensing and cooling operations and also such vapors as are evolved in the stabilizing operation may be recirculated through the condensing and cooling operations and eventually liquefied and brought into the gross liquid product and into the final product either entirely or to a very large degree. In the operation of our process either no venting or but little venting of such recirculation system is required. In our process pressure is not released until the stabilizing operation and there is no loss by weathering during the liquefying operations or other operations and the vapors evolved in stabilizing are returned to the condensing operation, unless necessarily vented.

We have further found that the effectiveness of complete stripping of the absorption medium is augmented by special precautions in the absorption operation. In this connection we avoid inefficiency of absorption due to heating of the absorption medium by heat of absorption and due to saturation of the absorption medium and to dislodgment therefrom of lighter hydrocarbons by more readily absorbed heavy hydrocarbons, as by carrying out the absorption operation in a plurality of stages by successively contacting the oil with separate bodies of stripped absorption medium. And to attain the advantages of refrigeration in the absorption operation but to attain them economically the absorption medium passing to the last or latter stages of absorption may be refrigerated while medium passing to earlier stages is merely cooled. And to attain to a high degree the advantages of using highly stripped absorption medium and of carrying out the absorption in multiple stages, we have found that a mechanical agitation of the absorption medium

producing intimate contact between the medium and the gas is of great value.

The use of thoroughly stripped absorption medium and the use of multistage absorption and the carrying out of such absorption under mechanical agitation, in accordance with our invention, are all features acting to increase the efficiency of the absorption operation; and it is apparent that these features actually cooperate in that the advantages of each feature are retained and augmented by the effect of the other features. The use of these features not only diminishes the necessity of using excessive quantities of absorption medium and of using the extensive and uneconomical cooling apparatus that is required in conjunction with the use of such excessive quantities of absorption medium, but these features render effective increases in the amount of absorption medium circulated. In prior practice increasing the amount of absorption medium circulated soon led to a condition at which large increases in the amount of absorption medium circulated produced but inconsequential increase in the efficiency of the gasoline producing plant but in the practice of our invention similar increases in the amount of absorption medium circulated produce increased efficiency. In other words increase in circulation beyond the point where such increase fails to produce an increase of efficiency in prior practice nevertheless produces substantial increase of efficiency in the practice of our invention.

The ideal condensation or compression and condensation of all absorbed hydrocarbons in a single stage of compression and condensation is not always practicable and in accordance with our invention still vapors that are not condensed in the first compressing and condensing operation are subjected to a second compression and condensation. Such multistage compression and condensation overcomes the practical difficulties and the principle of condensing lower-boiling hydrocarbons in the presence of higher-boiling hydrocarbons may be followed if necessary in such multistage compression and condensation by introducing into the second stage of compression and condensation some heavier gasoline hydrocarbons, for example, some of the liquid product of the first stage of compression and condensation. If conditions are such that the addition of some higher-boiling hydrocarbons to the second stage condensation will effect a condensation of more of the low-boiling hydrocarbons in that stage of condensation there will then be available a greater quantity of refrigeration, produced by evaporation of such lowboiling constituents, for use in the stabilizing operation. To a similar end, namely complete condensation of the low-boiling constituents, and with a view to effecting condensation of as large a proportion of still vapors as possible in a

single condensing operation, some or all of the condensed product of the second stage of condensation may be introduced, as by expanding, into the products that are under compression in the first stage of compression and condensation. In such case it may be desirable to carry the first stage of compression to a higher pressure; and in such case refrigeration and refluxing in the stabilizing step may be effected by recompressing and condensing vapors evolved in that step and expanding the resultant liquid in the stabilizer.

Conditions vary with respect to natural gas from different sources and it may be desirable to use the product of a second stage of compression and condensation merely for the purpose of producing the refrigeration necessary to economical final stabilization of the gross product.

In the production of gasoline from natural gas in accordance with our invention, and particularly by the employment of the several features thereof in conjunction, it is possible to obtain from natural gas much more gasoline that meets commercial requirements with respect to stability than the charcoal test and other well known tests indicate to be present in such natural gas.

30 In the practice of our invention as high a proportion as possible of the hydrocarbons of the natural gas is absorbed and advantageously whatever part of the absorbed hydrocarbons is not condensed is maintained in circulation and recirculation within the system as long as possible. To this end the vapors evolved in the stabilizing operation may be recirculated together with whatever vapors are not condensed in the condensing operation.

35 In the production of gasoline from natural gas the character of the natural gas treated or the conditions of operation of our invention may require that unsaturated hydrocarbons absorbed in the absorption medium from the natural gas or otherwise introduced therein must be removed from the absorption medium in order that such unsaturated hydrocarbons will not impair the absorptive power of that medium as by producing sludge in the absorption medium. In accordance with our invention such unsaturated hydrocarbons may be taken into the products subjected to compression and condensation and recirculation to the end that the treatment applied to those products may effect such polymerization of the unsaturated compounds as will increase the gasoline output. Such unsaturated compounds may be driven out of the absorption medium in any manner but if conditions are such that steam distillation must be employed in conjunction with fire distillation in order that the absorption medium may be sufficiently stripped, then such steam distillation will contribute to the removal of such un-

saturated compounds. If conditions are such that more efficient absorption of unsaturated compounds of the natural gas is brought about by the presence of unsaturated compounds in the absorption medium then absorption may be carried out in part, as in one of several stages of absorption, by the use of oil that contains unsaturated compounds but is otherwise sufficiently stripped to permit absorption of unsaturated hydrocarbons of the gas.

70 For the purpose of more fully disclosing our invention but as merely illustrative of the application thereof, the features of our process and of apparatus embodying and 80 suitable to the practice of our invention are described in connection with the accompanying drawings in which;

Fig. 1 is a diagrammatic illustration of apparatus embodying our invention and 85 whereby our invention may be practiced.

Fig. 2 is an elevation, partly in section, of the absorption apparatus.

Fig. 3 is a diagrammatic illustration of apparatus embodying a modification of our 90 invention and whereby a modification of our invention may be practiced, and

Fig. 4 is a detailed view of the stabilizer.

Referring to the drawings, natural gas is introduced to the absorber A that is supplied with an absorption medium, for example, mineral seal oil, and dry distillation of the absorption medium may be carried out by a dry or fire still B while steam distillation of the absorption medium may be carried out in the steam still C, a first stage of compression and condensation being carried out by the compressor and condenser D, and a second stage of compression and condensation being carried out by the compressor and condenser E. Stabilization is carried out by the stabilizer F and recirculation is carried out through the recirculating system G.

The absorber A comprises casing 1 into which natural gas is introduced through the inlet 3 and from which unabsorbed gas is discharged from the outlet 4. While the operation of the process and apparatus of our invention is described in connection with a liquid absorption medium, such as mineral seal oil, it is to be understood that any absorption medium may be used so long as appropriate modifications in the apparatus and mode of operation are made. The absorption is carried out in two stages in the absorber illustrated but any number of stages may be employed. The stripped oil is introduced through the pipes 9 and 10, the oil entering through the pipe 9 being withdrawn through the pipe 11 and the oil entering through the pipe 10 being withdrawn through the pipe 12. The oil entering through the pipes 9 and 10 discharges into pans 8 and eventually passes over the edges of those pans onto baffles 2 that direct the

oil into the next lower pan and the oil in each pan is acted upon by blades 5 mounted on a shaft 6 that is driven by a motor 7 and thus dispersed in fine particles so that the gas passing up through the absorber is brought into intimate contact with the absorption oil. Absorption oil entering through the pipe 10 first contacts with gas that has previously been in contact with absorption oil and from which heavier hydrocarbons which are more readily absorbed have thereby been removed. Thus the entering oil first absorbs lighter hydrocarbons but as it descends in the absorber some of such lighter hydrocarbons may be displaced by fresh quantities of heavier hydrocarbons coming in with the fresh gas; but the lighter hydrocarbons so displaced and any heavier hydrocarbons that are not absorbed by the oil entering through the pipe 10 are absorbed by the oil that enters through the pipe 9 and provides a second stage of absorption. Other stages of absorption including a stage in which the oil contains a relatively large proportion of unsaturated hydrocarbons may be similarly produced.

Low temperature and high pressure within the absorber facilitate absorption but the pressure and temperature commercially employed are dependent upon practical considerations such as the rate of circulation of the gas and oil and we have attained efficient results by maintaining about thirty pounds per square inch of pressure and atmospheric temperature within the absorber but lower temperature is desirable. Refrigeration of absorption medium passing to any stage of absorption may be readily effected as by passing it through refrigerating chamber 110 from which refrigerating medium passes through compressor 111, cooler 112, tank 113 and valve 114 back to chamber 110.

The absorption oil from the several absorption stages is all brought together as by the pipe 13 and if necessary may be passed to a vent tank 14 that is provided with a valve 15 that may be opened if the pressure becomes excessive. A pump 16 passes the saturated oil through a heat exchanger 17, where it takes up heat from the distilling step or steps, to the absorber. The hydrocarbon-bearing oil then passes to a preheater 18, the use of which is optional and which may be heated by fire or by steam, as by means of the steam inlet and outlet pipes 20 and 21.

The hydrocarbon-bearing oil is then subjected to dry or fire distillation in the fire still B. The fire still B may be a pipe still 99 of common construction operating in conjunction with a chamber or tower 100, in which case the preheater is not indispensable. Pipe still 99 may be heated by burner 99a. When a pipe still is used the oil is maintained at such a velocity therein that it will not be injured by heat but will attain a de-

sired final temperature, e. g. 400° F., and pass through the pipe 28a into chamber or tower 100 where it flows down over devices that will expose large surfaces for example baffles 101 that are provided with upwardly extending tubes 102 over which are placed caps 103, the oil level being maintained on each baffle by drain tubes 104. Or, the fire still B may be of the construction shown in Fig. 3 wherein an outer casing 22 encloses a cylindrical still 23 and a burner 24 that is arranged below the still so that the combustion gases pass up around the still and out through flue 25. One or more spray nozzles 26 within the still 23 direct hydrocarbon-bearing oil supplied through pipe 19 against the heated upper portion thereof, the desired pressure being maintained by manually regulating the number of nozzles 26 in position. Brief contact of hydrocarbon-bearing oil against an effective heat source and while in a divided state is thus effected. The burner 24 is so regulated that oil in the bottom of the still 23 will be at as high a temperature as possible without injuring the oil, for example, 400° F.

The vapors produced in the fire-distilling operation will pass through the pipe 28, that leads from still 23 or tower 100, to a knockout 29 that returns to the fire-distilling operation, e. g. to still 23 or tower 100, through pipe 30 any of the absorption medium that may have been carried off with the vapors. Vapors pass from knockout 29 through the pipe 31 to the compression and condensation operations, such vapors being then at a temperature of approximately 125° F. to 200° F.

The fire still may under favorable conditions, and particularly when a pipe still is used, sufficiently strip the absorption medium of absorbed hydrocarbons, or under less favorable conditions the absorbed hydrocarbons may thereby be reduced to $\frac{5}{6}$ ths of 1% or perhaps only to 1% or even 2%, these percentages being based upon standard distillation tests.

If the absorption medium is not or can not be sufficiently stripped in the fire still or if it be desired to remove unsaturated compounds from the absorption medium the absorption oil is passed from the fire-distilling operation, e. g. from still 23 or tower 100, through pipe 47 to a steam distillation operation in a steam still C.

The steam still C may consist of a casing 98 provided with suitable baffles 98a and is preferably maintained at a temperature that will prevent condensation that might produce emulsions. Absorption medium is passed from pipe 47 through trap 105 into casing 98 and steam is supplied thereto through pipe 107a by boiler 106, the steam being preferably but not necessarily superheated in superheater 107. Or, the steam still C may, as shown in Fig. 3, consist of casing 38 into which absorption medium is

passed directly from pipe 47 by means of pump 36, being sprayed therein from spray-heads 39. Casing 38 is supplied with steam, preferably superheated through pipe 107a and if necessary additional heat is supplied thereto by burner 40.

Stripped oil is returned from the steam distilling operation by pump 41 through heat exchanger 17 and cooling coils 42 to the 10 supply pipes of the various stages of the absorber, for example, the supply pipes 9 and 10. If it be desired to eliminate the steam still the valve 37 may be opened and the valve 37a closed.

15 Vapors are withdrawn from the steam distilling operation through pipe 42 that leads to the knockout 42a from which any collected liquid is returned to the steam still through pipe 42b. The knockout 42a is 20 preferably maintained at a temperature that will not return water to the steam still. Vapors pass from the knockout 42a through the pipe 43 to cooler 43a and condensed steam and hydrocarbons in liquid and vapor form 25 pass to the accumulator 44 which is provided with a water drain 44a and with a vapor line 45 that leads to the vapor pipe 31 if the valve 45a is open or to the vapor pipe 28 if the valve 45b is open.

30 The cooling effect in the knockout 29 is so conducted that vapors pass through the pipe 31 to the compressor 32 at 125° F. to 200° F.

Back pressure valves and vacuum control 35 valves and venting valves are suitably located throughout our apparatus and so controlled in connection with the operation of compressor 32 that the compressor is not overloaded and proper balance of pressure 40 is maintained throughout the system. We have obtained good results when a vacuum of two inches of mercury is maintained in the fire distilling operation by such balancing of pressure.

45 Compression of the vapors in compressor 32 increases the temperature thereof to approximately 280° F. and they pass through pipe 33 to condenser 34 in which the temperature is reduced by good atmospheric or water cooling and the resulting liquid and remaining vapors pass to accumulator tank 35. Vapors are withdrawn from accumulator tank 35 through pipe 49a to the second stage compressor 49 in which the temperature 50 of the vapors is raised and the vapors are passed through pipe 50a to condenser 50 in which the temperature of the vapors is reduced by good atmospheric or water cooling and the resulting liquid and remaining vapors pass to the accumulator tank 51.

Under one mode of operation the compressors 32 and 49 are so operated that in spite of resulting condensation the pressure in accumulator tank 51 is maintained at about 225 to 250 pounds per square inch. Pressure

varies in accumulator tank 35 but may be between 25 and 50 pounds per square inch.

Gasoline hydrocarbons collected in the accumulator tank 44 as a result of the distillation may be withdrawn from the system through the valve 70 or may be passed to 71 the pump 71 which delivers those condensed hydrocarbons into the pipe 33, if valve 72 is open, and thus into the vapors compressed in the first stage of compression. Or, those hydrocarbons may be passed, if the valve 73 is open, into the still or vaporizer 48 heated by the burner 48a from which the vaporized hydrocarbons are led by pipe 74 to the pipe 45 from which they may be passed either 81 to the pipe 28 or the pipe 31 as above described. If for any reason such as preventing impairment of the color of the final product, a residue is retained in the still 48 it may be drained therefrom by the valve 75, 81

If it be desired to bring into the vapors in the second stage of compression and condensation some of the hydrocarbons condensed in the first stage of compression and condensation such hydrocarbons may be withdrawn from the accumulator 35 by means of the pipe 76 and passed by means of pump 77 into the pipe 50a leading to the second stage condenser. If it be desired to conduct into the vapors undergoing the first stage of condensation and compression liquid hydrocarbons collected in accumulator tank 51, this may be done by conducting liquid from the accumulator tank 51 through pipe 177 and expanding it into the chamber 78 in the pipe 1 33 or expanding it in the chamber 79. With this mode of operation the compressor 32 may be so designed and operated that the pressure in the accumulator tank 35 may be maintained, with a view to condensing as 1 much liquid therein as possible, at a pressure higher than the pressure occurring therein when liquid from the second condensation is not so expanded.

Uncondensed vapor from accumulator tank 1 51 is conducted by pipe 52a through a pre-heater 52 where its temperature is raised to 450° F. to 500° F. and it is then returned to the system either through the pipe 27a to the hydrocarbon-bearing oil entering the fire 1 still or through the pipe 27b to the chamber 100 or through the pipe 27c to the vapor pipe 28 or through the pipe 27d to the vapor pipe 31. In the construction shown in Fig. 3 such recirculation vapor may be carried into the 1 still 23 through the pipe 27a and discharged through nozzles 27 toward the bottom of the still 23 so as to assist in agitation of the absorption medium therein. The point at which such recirculation vapors are returned 1 to the system will depend upon the operating conditions, for example, upon the character of the recirculation vapors or upon the extent to which it is necessary to keep such recirculation vapors out of contact with the 1

absorption medium in order to prevent an accumulation of unsaturated hydrocarbons therein. Knockouts 96 remove lubricating oil from compressed vapors.

- 5 In order to remove from the liquid hydrocarbons collected in accumulators 35 and 51 such hydrocarbons as will not remain therein at temperatures and pressures commercially required and in order to remove such hydrocarbons without loss of hydrocarbons that will remain liquid under such temperatures and pressures, the collected liquid hydrocarbons are stabilized in the stabilizer F. The stabilizer F comprises a casing 152 with-
 10 in which there are several pressure reduction chambers 54, 55 and 56 that are formed by tube-sheets 53 that are joined by tubes 53'. Liquid hydrocarbons from high pressure accumulators tank 51 are introduced by pipe 51a into upper pressure reduction chamber 54 and conducted from the bottom of chamber 54 to the next lower pressure reduction chamber 55 through a pipe 57 having a bend 58 that ensures that chamber 54 is kept substantially full. Any liquid that is not evaporated by pressure reduction will pass from the lower portion of chamber 55 through the bend 58a and be discharged through pipe 59 within the stabilizer casing 52. Vapors evolved in the
 15 chambers 54 and 55 pass through pipe 60 and are liberated at 61 in the vicinity of liquid passing out of pipe 59. Liquid hydrocarbons from accumulator tank 35 enter pressure reduction chamber 56 through pipe 35a, leave
 20 that chamber through the bend 62 that maintains chamber 56 substantially full and are discharged through pipe 63 within the casing 52. Vapors evolved in chamber 56 pass from the top thereof through pipe 64 and are dis-
 25 charged through pipe 65 within casing 52 in the vicinity of liquid passing from pipe 63. Vapors evolved by the reduction of pressure of the liquid hydrocarbons from high stage accumulator tank 51 are thus subjected to re-
 30 frigeration produced by evolution of those vapors as those vapors pass up through the tubes 53' of the chamber 54 and 55. Vapors evolved by reduction of pressure on liquid hydrocarbons from low stage accumulator tank
 35 35 are subjected to refrigeration produced by reduction of pressure on both quantities of liquid hydrocarbons, by passing up through tubes 53' of chambers 54, 55 and 56. Any vapors that are not condensed by such refrigeration are vented from chamber 52 through pipe 52b and compressor 52c into recirculation pipe 52a. Excess recirculation vapors are vented when necessary to preserve proper pressure conditions throughout the system as
 40 by vent valves 80 that should be so located and controlled as to vent the least desirable vapors.

If liquids collected in accumulator tank 51 do not provide sufficient refrigeration, for example, in the case where such liquids are ex-

panded into the chamber 78 or 79 then vapors may be withdrawn from the top of the stabilizer casing 52 through the pipe 81 compressed by compressor 82, condensed in condenser 83 and returned to pressure reduction chamber 54 of stabilizer 52 through pipe 51a, uncondensed vapors being introduced into recirculation pipe 52a by pipe 51b.

Liquid hydrocarbons collecting in the bottom of stabilizer 52 pass through pipe 67 to kettle 68 in which the temperature is raised to desired temperature and evolved gases are passed through pipe 68' back to the stabilizer 52 wherein they are again subjected to refrigeration. The finished product may be withdrawn through the valve 90. Baffle plates 69 of any suitable configuration may be positioned within the stabilizer casing 52. Briefly, the function of the stabilizer is to remove in vapor form from the hydrocarbons liquefied by compression and cooling, such light hydrocarbons as are ordinarily in vapor form at atmospheric temperature and pressure, and to remove such light hydrocarbons in such a way that their vapors will not carry away with them the vapors of hydrocarbons which are desired in the final liquid product, and to remove such light hydrocarbons to such an extent that the final liquid product will possess a vapor pressure low enough to permit them to be handled by usual methods without danger. In the stabilizer, vapors are evolved from the total liquid produced, which vapors consist of such undesirably light hydrocarbons.

From the foregoing it is apparent that we have described numerous features that each contribute to the efficiency of the absorption of gasoline from natural gas and that co-operate with one another to retain and augment the advantages of each feature; and it is apparent that the several features described may be selected in accordance with conditions of operation to the end that the best results may be obtained. For example we have obtained much more gasoline from natural gas than is indicated by well known tests to be present in such gas, merely by using a fire still and two stages of compression and condensation together with either a two stage mechanical absorption or mere static absorption and together with recirculation even though the stripped oil contained as much as 2% of hydrocarbons. Obviously the various temperatures and pressures above set forth are stated as illustrations and may be varied to suit varying conditions of operation.

From the foregoing, it is apparent that the steps of our invention whereby hydrocarbon vapors are liquefied are useful in the liquefaction of any body of hydrocarbon vapors regardless of the manner in which such vapors are produced and even in the liquefaction of waste gases that are produced at va-

rious stages in petroleum refineries and in the production and handling of crude oil generally. It is also apparent that the distilling steps of our invention are applicable to distilling operations generally where it is desired to effect a complete or substantially complete separation of the desired hydrocarbons from other hydrocarbons without undesirably altering the residue, and also where it is desired to free the residue entirely or to a high degree of lighter hydrocarbons. It is also apparent that the absorption and stabilizing steps of our process are susceptible of general application and are not limited to the treatment of natural gas and of products derived therefrom.

What we claim and desire to secure by Letters Patent of the United States is:

1. In the production of gasoline from natural gas by a method wherein hydrocarbons are absorbed from natural gas by an absorption medium, the steps comprising subjecting the medium charged with absorbed hydrocarbon vapors to dry distillation and then separately to steam distillation, separately withdrawing evolved hydrocarbon vapors from said distilling operations, admixing the hydrocarbon vapors so withdrawn, and subjecting the admixed vapors to compression and cooling.

2. In the production of gasoline from natural gas by a method wherein hydrocarbons are absorbed from natural gas by an absorption medium, the steps comprising subjecting the medium charged with absorbed hydrocarbon vapors to dry distillation and then separately to steam distillation, separately withdrawing evolved hydrocarbon vapors from said distilling operations, admixing the hydrocarbon vapors so withdrawn, subjecting the admixed vapors to compression while said vapors contain substantially all of the heavier constituents absorbed by said medium and expelled therefrom by said distillation, and cooling the compressed vapors.

3. In the production of gasoline from natural gas by a method wherein hydrocarbons are absorbed from natural gas by an absorption medium, the steps comprising subjecting the medium charged with absorbed hydrocarbon vapors to dry distillation and then separately to steam distillation, separately withdrawing evolved hydrocarbon vapors from said distilling operations, admixing the hydrocarbon vapors so withdrawn, compressing and cooling the admixed vapors, and recirculating into contact with the absorption medium in the dry distilling operation vapors of lower boiling hydrocarbon constituents, that are normally in vapor form under substantially atmospheric pressure and temperature, of hydrocarbons that have passed through said compressing and cooling operations.

4. In the production of gasoline from nat-

ural gas by a method wherein hydrocarbons are absorbed from natural gas by an absorption medium, the steps comprising subjecting the medium charged with absorbed hydrocarbon vapors to dry distillation and then separately to steam distillation, separately withdrawing evolved hydrocarbon vapors from said distilling operations, admixing the hydrocarbon vapors so withdrawn, compressing and cooling the admixed vapors, reheating vapors of lower boiling hydrocarbon constituents, that are normally in vapor form under substantially atmospheric pressure and temperature, of hydrocarbons that have passed through said cooling operation, and passing said reheated vapors into contact with the absorption medium in the dry distilling operation.

5. In the production of gasoline from natural gas by a method wherein hydrocarbons are absorbed from natural gas by an absorption medium, the steps comprising subjecting the medium charged with absorbed hydrocarbon vapors to dry distillation and then separately to steam distillation, separately withdrawing evolved hydrocarbon vapors from said distilling operations, admixing the hydrocarbon vapors so withdrawn, compressing and cooling the admixed vapors, stabilizing by rectification the resulting condensate, reheating hydrocarbon vapors evolved in the stabilizing operation, and passing the reheated vapors into contact with absorption medium in the dry distilling operation.

6. In the production of gasoline from natural gas by a method wherein hydrocarbons are absorbed from natural gas by an absorption medium, the steps comprising subjecting the medium charged with absorbed hydrocarbon vapors to dry distillation and then separately to steam distillation, separately withdrawing evolved hydrocarbon vapors from said distilling operations, admixing the hydrocarbon vapors so withdrawn, subjecting the admixed vapors to compression and cooling, stabilizing by rectification the resulting condensate, and passing vapors evolved in the stabilizing operation into contact with the absorption medium in the dry distilling operation.

7. In the production of gasoline from natural gas by a method wherein hydrocarbons are absorbed from natural gas by an absorption medium, the steps comprising distilling absorbed hydrocarbons from the charged absorption medium, subjecting to compression all of the evolved hydrocarbon vapors while said vapors contain substantially all of the heavier constituents absorbed by said medium and expelled therefrom by said distillation, cooling the compressed vapors, stabilizing the condensate by rectification, reheating vapors evolved in the stabilization, and adding the reheated vapors to the vapors passing to the compressing operation.

8. In the production of gasoline from natural gas by a method wherein hydrocarbons are absorbed from natural gas by an absorption medium, the steps comprising distilling absorbed hydrocarbons from the charged absorption medium, subjecting the evolved hydrocarbon vapors to compression and cooling, stabilizing the condensate by rectification, reheating vapors evolved in the stabilizing operation, and adding the reheated vapors to the vapors evolved by said distillation and passing to the compressing operation.

9. In the production of gasoline from natural gas by a method wherein hydrocarbons are absorbed from natural gas by an absorption medium, the steps comprising distilling absorbed hydrocarbons from the charged absorption medium, condensing the vapors evolved in the distilling operation, stabilizing by rectification the condensate of the condensing operation, recirculating the vapors evolved in the stabilizing operation into contact with absorption medium in the distilling operation.

10. In the production of gasoline from natural gas by a method wherein hydrocarbons are absorbed from natural gas by an absorption medium, the steps comprising subjecting the absorption medium charged with hydrocarbons of the natural gas to dry distillation to remove substantially all absorbed hydrocarbons that can be so removed without substantial injury to the medium and then separately to steam distillation, separately withdrawing from said distilling operations the hydrocarbon vapors evolved therein, admixing the hydrocarbon vapors so withdrawn, and subjecting the admixed hydrocarbon vapors, to compression and cooling.

11. In the production of gasoline from natural gas by a method wherein hydrocarbons are absorbed from natural gas by an absorption medium, the steps comprising multiple absorption by dispersed absorption medium, subjecting the absorption medium to dry distillation and then to steam distillation, separately withdrawing and then admixing the vapors evolved in said distilling operations, compressing and cooling the admixed vapors prior to removal therefrom of a substantial quantity of heavier constituents, stabilizing the condensate of the cooling operation, reheating uncondensed vapors of hydrocarbons that have passed through said cooling operation and said stabilizing operation, recirculating the heated vapors into contact with absorption medium in the dry distilling operation, and returning stripped absorption medium from said steam distilling operation to each of said absorption stages.

12. In the production of gasoline from natural gas by a method wherein hydrocarbons are absorbed from natural gas by an absorp-

tion medium, the steps comprising distilling absorbed hydrocarbons from the absorption medium by the use of heat and light hydrocarbon vapor, then in a separate operation distilling unsaturated hydrocarbons from the absorption medium by use of steam, returning the stripped absorption medium to the absorption operation, and bringing together and compressing and then cooling all of the hydrocarbon vapors evolved from the charged absorption medium together with said light hydrocarbon vapors.

13. In the production of gasoline from natural gas by a method wherein hydrocarbons are absorbed from natural gas by an absorption medium, the steps comprising subjecting the charged absorption medium to steam distillation with superheated steam, and then subjecting to compression all of the hydrocarbons so distilled off while said vapors contain substantially all of the heavier constituents absorbed by said medium and expelled therefrom by distillation, and then cooling the compressed vapors.

14. In the production of gasoline from natural gas by a method wherein hydrocarbons are absorbed from natural gas by an absorption medium, the steps comprising contacting the natural gas successively with separate parallel streams of absorption medium, stripping the charged absorption medium after its contact with the gas to a point at which it contains less than .6% of absorbed hydrocarbons, and feeding the stripped absorption medium to each of said separate streams.

15. In the production of gasoline from natural gas by a method wherein hydrocarbons are absorbed from natural gas by an absorption medium, the steps comprising maintaining separate parallel streams of absorption medium, mechanically agitating the absorption medium of said streams to bring it to a finely divided state, successively contacting natural gas with the resulting bodies of finely divided absorption medium, and separately withdrawing the absorption medium of said streams from contact with the gas.

16. In the production of gasoline from natural gas by a method wherein hydrocarbons are absorbed from natural gas by an absorption medium, the steps comprising contacting the natural gas successively with separate parallel streams of absorption medium, bringing together absorption medium from said streams after contact with the gas, stripping the absorption medium of absorbed hydrocarbons to a point at which they contain less than 1% thereof, feeding stripped absorption medium to each of said streams, compressing and cooling the vapors evolved in said stripping operation, and recirculating to the system at a point thereof between said absorbing operation and said compressing operation vapors of lower boiling hydrocarbon

constituents, that are normally in vapor form under substantially atmospheric pressure and temperature, of hydrocarbons passing through said compressing and cooling operations.

- 5 17. In the production of gasoline from natural gas by a method wherein hydrocarbons are absorbed from natural gas by an absorption medium, the steps comprising 10 multistage absorption by dispersed absorption medium, dry distillation of the charged absorption medium with separate withdrawal of hydrocarbon vapors evolved, followed by steam distillation of the absorption medium 15 with separate withdrawal and subsequent admixture of vapors evolved, compression and cooling of the admixed hydrocarbons distilled off in said distilling operations, recirculation into contact with the oil in the dry 20 distilling operation of vapors of lower boiling hydrocarbon constituents, that are normally in vapor form under substantially atmospheric pressure and temperature, of hydrocarbons passing through said compressing 25 and cooling operation, and feeding absorption medium withdrawn from the steam distillation to each absorption stage.

18. In the production of gasoline from natural gas by the use of a liquid medium 30 for absorbing hydrocarbons from natural gas, the steps comprising maintaining a plurality of separate parallel streams of absorption medium, contacting the natural gas successively with said streams, separately with- 35 drawing said streams from contact with the gas, bringing together the absorption medium flowing from said streams and subjecting it to dry distillation and then separately to steam distillation and thereby thoroughly 40 stripping the medium of absorbed hydrocarbons, and then supplying each of said streams with stripped absorption medium from the steam distilling operation.

- 45 19. In the production of gasoline from natural gas by a method wherein hydrocarbons are absorbed from natural gas by an absorption medium, the steps comprising dry distilling the absorption medium, then steam distilling the absorption medium after re- 50 moval from contact therewith of hydrocarbon vapors evolved in the dry distilling operation, and compressing together while hot the hydrocarbons evolved in said distilling operation and condensing the resulting 55 vapors.

20. In the production of gasoline from natural gas by a method wherein hydrocarbons are absorbed from natural gas by an absorption medium, the steps comprising dry 60 distilling the absorption medium, then steam distilling the absorption medium after removal from contact therewith of hydrocarbon vapors evolved in the dry distilling operation, compressing together while hot the hydrocarbons evolved in said distilling op-

erations, cooling the compressed vapors, stabilizing the condensate by rectification, reheating vapors evolved in the stabilization and recirculating them to the vapors passing the compressing operation.

70

21. In the production of gasoline from natural gas by a method wherein hydrocarbons are absorbed from natural gas by an absorption medium, the steps comprising distilling of absorbed hydrocarbon vapors from the charged absorption medium, subjecting substantially all of the vapors evolved in the distilling operation to high compression and temperature while said vapors contain substantially all of the heavier constituents absorbed by said medium and expelled therefrom by distillation, cooling the compressed vapors, stabilizing the condensate, and reheating and returning to the system at a point between the absorption operation and the compressing operation vapors evolved in the stabilizing operation.

80

22. In the production of gasoline from natural gas by a method wherein hydrocarbons are absorbed from natural gas by an absorption medium, the steps comprising contacting the gas successively with separate dispersed bodies of absorption medium, separately withdrawing said bodies from contact with the gas, subjecting the charged me- 90 dium to dry distillation to remove substantially all absorbed hydrocarbons that can be so removed without injury to the medium, thereafter thoroughly stripping the absorption medium of absorbed hydrocarbons including unsaturated hydrocarbons, and feeding stripped absorption medium to each of said bodies thereof.

95

23. In the production of gasoline from natural gas by a method wherein hydrocarbons are absorbed from natural gas by an absorption medium, the steps comprising dry distilling the absorption medium, then steam distilling the absorption medium, condensing the steam from the vapors of the steam distilling operation, vaporizing hydrocarbons condensed in said condensing operation, combining said last named vapors and uncondensed vapors of said condensing operation and vapors of said dry distillation, and compressing and cooling said combined vapors.

24. In the production of gasoline from natural gas by a method wherein hydrocarbon vapors are absorbed from natural gas by an absorption medium and distilled therefrom and condensed and the condensate is stabilized, the steps comprising combining in vapor phase under pressure hydrocarbon vapors evolved in the distilling operation and in the stabilizing operation, and passing the compressed vapors to the condensing operation.

25. In the recovery of liquefiable hydrocarbons from a mixture of hydrocarbon vapors by the use of an absorption medium, the steps comprising distilling from the charged

- absorption medium by dry distillation such hydrocarbons as may be so distilled without undesirable alteration of the absorption medium, then subjecting the absorption medium to steam distillation after removal from contact therewith of hydrocarbon vapors evolved in the dry distillation, then bringing together the hydrocarbon vapors evolved in said distillations and compressing and cooling said vapors stabilizing the condensate after removal from contact therewith of uncondensed vapors of said cooling operation, and reheating and recirculating to the dry distilling operation vapors evolved in the stabilizing operation.
26. Apparatus for obtaining hydrocarbons from natural gas which comprises a plurality of absorption elements, means for passing streams of absorption medium in parallel through said elements, means for passing natural gas through said elements in series, a dry still and a steam still connected in series and adapted to receive charged absorption medium from said elements, and means for returning stripped medium to each of said elements from said steam still, and means for separately withdrawing from said stills hydrocarbon vapors evolved therein and for bringing said vapors together.
27. In apparatus for the treatment of hydrocarbons recovered from absorption medium charged with hydrocarbons by contact with natural gas, a compressor for hydrocarbon vapors distilled from the absorption medium, a condenser receiving compressed vapors from said compressor, means for stabilizing by rectification condensate formed in said condenser and thereby liberating vapors from said condensate, a heater, means for passing hydrocarbon vapors liberated in said stabilizer into said heater, and means for conducting heated vapors from said heater and mixing them with vapors passing to said compressor.
28. In apparatus for the treatment of absorption medium charged with hydrocarbons by contact with natural gas, a dry still for the charged absorption medium and having an outlet for evolved hydrocarbon vapors, a steam still having an outlet for evolved hydrocarbon vapors, means for conducting absorption medium from said dry still to said steam still, means for bringing together hydrocarbon vapors from said outlets, means for condensing said vapors, means for stabilizing by rectification and in the absence of vapors not condensed in said condensing means condensate formed in said condensing means, means for reheating hydrocarbon vapors evolved in said stabilizing means, and means for conducting hydrocarbon vapors from said reheating means in contact with absorption medium in said dry still.
29. In apparatus for the treatment of absorption medium charged with hydrocarbons
- by contact with natural gas, a fire still for charged absorption medium and having an outlet for evolved hydrocarbon vapors, a steam still having an outlet for evolved hydrocarbon vapors, means for conducting absorption medium from said first still to said steam still, a compressor, means for conducting to said compressor all of the hydrocarbon vapors from both of said outlets, and a condenser receiving compressed vapors from said compressor.
30. In apparatus for the treatment of absorption medium charged with hydrocarbons by contact with natural gas, a fire still for charged absorption medium and having an outlet for evolved hydrocarbon vapors, a steam still having an outlet for evolved hydrocarbon vapors, means for conducting absorption medium from said fire still to said steam still, a compressor, means for conducting to said compressor all of the hydrocarbon vapors from both of said outlets, a condenser receiving compressed vapors from said compressor, means for stabilizing by rectification and in the absence of uncondensed vapors from said condenser the condensate formed in said condenser, means for reheating hydrocarbon vapors evolved in said stabilizing means, and means for introducing hot vapors from said re heater into said compressor with vapors from said stills.
31. In apparatus for the absorption of hydrocarbons in an absorption medium by contact thereof with natural gas, means for maintaining a plurality of separate bodies of absorption medium in dispersed form, means for passing natural gas successively into contact with said bodies of absorption medium, means for separately withdrawing said bodies from contact with the gas, means for subjecting to steam distillation absorption medium from said bodies, and means for conducting absorption medium from said distilling means separately to each of said bodies of absorption medium.
32. In apparatus for the absorption of hydrocarbons in an absorption medium by contact thereof with natural gas, means for maintaining a plurality of separate streams of absorption medium, means for passing natural gas successively into contact with said streams, means for bringing together absorption medium from said streams after removal thereof from contact thereof with natural gas, means for distilling absorbed hydrocarbons from the absorption medium so brought together and including means for steam distilling said absorption medium, and means for feeding to said streams separately absorption medium from said distilling means.
33. In apparatus for the treatment of absorption medium charged with hydrocarbons by contact with natural gas, a still for absorption medium charged with hydrocarbons from natural gas, means for heating by fire

- charged absorption medium fed to said still, a steam still, means for conducting absorption medium from said fire still to said steam still, means for separately withdrawing from said stills hydrocarbon vapors evolved therein, means for subjecting to high compression together and while still hot hydrocarbon vapors withdrawn from said stills, a condenser for vapors compressed in said compressing means, means for heating lighter hydrocarbons from said condenser, and means for heating lighter hydrocarbons from said condenser, and means for conducting hot hydrocarbon vapors from said heater into contact with absorption medium in said first still. 5
34. In the production of gasoline from natural gas by a method wherein hydrocarbons are absorbed from the gas by an absorption medium, the steps comprising subjecting vapors evolved in distillation of absorbed hydrocarbons from the absorption medium to compression and condensation, compressing the uncondensed vapors of said first condensing operation, adding to the compressed vapors liquid hydrocarbons produced in said first condensing operation and cooling the resulting mixture. 10
35. In the production of gasoline from natural gas by a method wherein hydrocarbons are absorbed from the gas by an absorption medium, the steps comprising subjecting vapors evolved in distillation of absorbed hydrocarbons from the absorption medium to compression and condensation, compressing and cooling the remaining vapors and refluxing to the first cooling operation liquid hydrocarbons produced in said second cooling operation. 15
36. In the production of gasoline from natural gas by a method wherein hydrocarbons are absorbed from the gas by an absorption medium, the steps comprising subjecting vapors evolved in distillation of absorbed hydrocarbons from the absorption medium to compression and cooling, compressing and cooling the remaining vapors, refluxing to the first cooling operation liquid hydrocarbons produced in said second cooling operation, stabilizing the liquid product of the first compressing and cooling operation and recondensing and expanding in said stabilizing operation vapors evolved in said stabilizing operation. 20
37. In the production of gasoline from natural gas by a method wherein hydrocarbons are absorbed from natural gas by an absorption medium and distilled therefrom and the still vapors are condensed and the condensate is stabilized, the steps comprising subjecting the absorption medium charged with hydrocarbons by contact with the natural gas to distillation wherein it is subjected under a pressure not substantially exceeding atmospheric pressure to the action of heat and re- 25
- heated vapors evolved in the stabilizing operation and steam, compressing and cooling the hydrocarbon vapors evolved in the distilling operation, stabilizing the condensate, reheating hydrocarbon vapors evolved in the stabilizing operation and passing them to the distilling operation. 70
38. Apparatus for the treatment of absorption medium charged with hydrocarbons by contact with natural gas comprising, a still for separating absorbed vapors from the charged medium, means for subjecting to condensing conditions the vapors evolved in said still, stabilizing means for the resulting condensate, and means for conducting vapors evolved in said stabilizing means into contact with charged absorption medium in said still. 75
39. In the production of gasoline from natural gas by a method wherein hydrocarbon vapors are absorbed from the natural gas by an absorption medium and distilled therefrom and the condensate is stabilized, the steps comprising distilling absorbed hydrocarbons from the charged absorption medium by distillation including steam distillation, substantially freeing of steam the vapors evolved in the distilling operation and then compressing said vapors while said vapors contain substantially all of the heavier constituents absorbed by said medium and expelled therefrom by said distillation, cooling the compressed vapors, stabilizing the resulting condensate, and recirculating to the system at a point between the absorption operation and the compressing operation vapors of lower boiling hydrocarbon constituents, that are normally in vapor form under substantially atmospheric pressure and temperature, of hydrocarbons that have passed through said compressing and cooling operations. 80
